TILTING AND SWIVEL CHAIR

Max Stoll, Brooklyn, N. Y.

Application July 5, 1935, Serial No. 29,851

1 Claim. (Cl. 155—90)

My invention relates to swivel seat chairs and in more detail to a swivel seat chair in which the seat is also tilttable and rotatable.

The chairs in use at present are of many different kinds but they all although rotatable can only tilt in one direction or are only tilttable and not rotatable or have no framework or foot rest.

An object of my invention is to construct a tilting swivel chair or seat in which the tilting can be in any direction and in which only the seat tilts.

Another object of my invention is to construct a chair in which the locking means to hold the seat in a raised or lowered position is continuously held in line so as to permit the seat to be easily locked.

A further object of my invention is to construct a strong, simple, durable and easily fashioned swivel and tilting chair or seat.

Another object of my invention is to construct a swivel, revolving, adjustable elevating chair with legs.

I accomplish these and other objects by providing inside the upper end of a tube a key-wayed bushing and inside the bushing a keyed shaft and providing holes in the tube and bushing and openings in the shaft, all the holes and openings being aligned together, and constructing at the head of the shaft a ball and spring swivel joint and above the swivel joint a rotating means carrying a seat and placing at the lower end of the shaft a plate and spring and constructing at the outside of the tube near its upper end a locking spring means which can extend into the holes in the tube, bushing and shaft to lock the parts in place.

Further and more specific details and objects of my invention will be shown and described in the accompanying drawing and specification.

Fig. 1 is an elevation partly in section showing my swivel chair with legs added. Fig. 2 is a section along the line 2—2 of Fig. 1. My chair in general may be divided into parts such as the raising means 1, frame work 2, locking mechanism 3, swivel mechanism 4 and tilting mechanism 5.

The chair can be either anchored to the floor in which case it would be provided with a slightly enlarged base 6 at its lower part or it may be provided with legs 7 properly attached and with the cross piece 8 added for strength and as a foot rest.

The raising mechanism 1 is comprised of a spring 9 which rests on the base 6. The spring 55 may be a coiled spring as shown or any other suit-

able type. The upper part of the spring rests against a plate 10 which is attached by a screw 11 to the lower end of the shaft 12. The supporting frame 2 comprises a tube 2A which extends upward from the base 6 encasing the spring plate 10 and part of the shaft. Inside the tube at its upper part is a bushing 13 which is provided with a key way 14. The shaft 12 is provided with a key 15 corresponding to and fitting into the key way of the bushing. As the bushing is secured in the tube so that it cannot turn, the shaft cannot turn and so can only be raised or lowered, the key always riding in the key way.

At the upper end of the tube 2A the locking mechanism 3 is constructed on a flange 16 at 15 its under side. The legs 7 are also attached at their upper ends to the under side of this flange. The locking mechanism 3 comprises a spring 17 abutting the under side of the flange and the angled part 18 pivoted at 19 to the flange. The part 18 is provided with one arm 20 resting against the spring 17 and another arm 21 extending downward from the pivot. The arm 21 terminates in a handle 22 and a projecting part 23. The tube and bushing are provided with 25 an opening 23A so that the projecting part 23 can extend therethrough. The shaft is notched at various places 24 aligned with the opening in the tube and bushing so that the projecting part 23 can catch in the notches 24 of the shaft. The 30 spring 17 pushes the arm 20 downward and causes the projecting part 23 to hold firmly against the notches 24. As the shaft cannot rotate the notches will always be aligned with the projecting part 23 making the locking of the 35 shaft easy.

The tilting mechanism is constructed at the head of the shaft by placing the ball 25 in the bearing 26 in the shaft end face. The upper part of the ball is provided with the extension 27. 40 The ball 25 is held in the bearing 26 by the threaded cap 28 which fits around the ball and threads onto the end of the shaft. Just below the cap, the shaft is provided with the flange 29 against which the spring 30 rests. The spring 30 is coiled about the ball and cap and extends between the flange 29 and the under part of the bearing 26, and permits the seat 32 to be tilted but provides compression to hold it properly. The ball and its extension with the nut 33 at its 50 end holds the spring in and keeps the seat properly positioned on the end of the shaft.

The swivel mechanism 4 comprises the bearing 31 which is constructed with the two plates 34A and 34 separated by the balls 35 which travel 55

in the groove 36 in the adjacent faces of the plates. The nut 23 rests against the upper surface of the plate 24 and holds the two plates together as the spring presses against the under 5 surface of the lower plate while the extension 27 extends through the plates to carry the nut 23. In this way the seat is provided with both a swivel and a tilting mechanism. The under part 10 of the seat is provided with the cut out part 37 for the nut and the end of the extension and the upper plate is attached to the under part of the seat in any appropriate manner.

As the details described and the drawing shows very specifically certain improvements for an improved tilting swivel chair and since many modifications and changes may be made in the same invention without changing or departing from the spirit and scope of the ideas conveyed in the specific description and so I desire to cover all 15 20 modifications, forms and embodiments of my ideas coming within the language and scope of the appended claim.

I claim:

An adjustable, swivel, tilting chair having a tube, a keywayed bushing in the tube, a shaft keyed at its lower end and extending into the keywayed bushing and at its upper end threaded and flanged, spring means inside the tube below the shaft, locking means attached to the tube and acting to lock the shaft, a concave ball socket in the flanged end of the shaft, a ball resting in the socket, an extension projecting upward from the ball threaded at its end, a threaded, hollow cap having an opening through which the extension projects fitting over the ball and threaded into the end part of the shaft, a swiveling means attached to the end of the extension from the 15 ball, a spring encasing the ball and extension and extending between the flange of the shaft and the under side of the swiveling means and a seat on the swiveling means.
